UNITED STATES PATENT OFFICE.

FRIEDRICH HINDERER, OF NEW ORLEANS, LOUISIANA.

DESIGN FOR A PLANT OR FLOWER BOX.

SPECIFICATION forming part of Design No. 36,679, dated December 15, 1903.

Application filed October 7, 1903. Serial No. 176,159. Term of patent 3½ years.

To all whom it may concern:

Be it known that I, FRIEDRICH HINDERER, a citizen of the United States, residing at 1114 Camp street, New Orleans, in the parish of Orleans, State of Louisiana, have invented a new, original, and ornamental Design for a Plant or Flower Box, of which the following is a specification, reference being had to the accompanying drawing, forming part thereof.

10 The figure is a perspective view showing the box.

What I claim as new and original, and desire to secure by Letters Patent, is—

The ornamental design for a plant or flower box, as shown.

In testimony whereof I have signed my name to this specification in the presence of two subscribing witnesses.

FRIEDRICH HINDERER.
